(57) **CLAIM**

The ornamental design for a hexagonal float, as shown and described.

DESCRIPTION

FIG. 1 is a perspective view of the hexagonal float showing my new design.

FIG. 2 is a bottom perspective thereof.

FIG. 3 is side view thereof.

FIG. 4 is another side view thereof.

FIG. 5 is another side view thereof.

FIG. 6 is another side view thereof.

FIG. 7 is top view thereof; and,

FIG. 8 is a bottom view thereof.

The broken lines showing other parts of the hexagonal float form no part of the claimed design.

1 Claim, 8 Drawing Sheets

FIG. 1

FIG. 2

FIG. 3

FIG. 4

FIG. 5

FIG. 6

FIG. 7

FIG. 8
